United States Patent Office.

DAVID PHILIPS, OF CORDOVA, ILLINOIS.

Letters Patent No. 82,844, dated September 22, 1868.

IMPROVED WAGON-BRAKE.

The Schedule referred to in these Letters Patent and making part of the same.

TO ALL WHOM IT MAY CONCERN:

Be it known that I, DAVID PHILIPS, of Cordova, in the county of Rock Island, and State of Illinois, have invented certain new and useful Improvements in Wagon-Brake; and do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My apparatus is designed for attachment to wheeled vehicles of all kinds which require brakes, such as wagons, carriages, and railroad-cars, but is intended more especially for use on wagons and other vehicles drawn by animal power.

In the drawings—

Figure 1 is a side elevation of a wagon with my brake attached.

Figure 2 is a top plan view of the same, with a portion of the wagon-body broken away, so as to show all parts of the brake.

A represents the body or box of the wagon, to the under side of which are attached two metal brackets, E, one on each side, just forward of the rear wheel, as clearly shown in figs. 1 and 2. These brackets are provided with a slot or opening extending from the front end back into the bracket some distance.

In these brackets I mount a bar or shaft, D, preferably of metal, which lies across under the body of the wagon, and reaches out on line with the outside of the wheel on each side of the body, and has rub-blocks K attached to the ends in such a manner that they may revolve upon the shaft but not move sidewise.

Near one end of this shaft I attach a lever, C, one end of which extends up by the side of the wagon-body, as shown in fig. 1, and the other end, b, of which projects below the shaft a short distance, and is pivoted to one end of rod F, the other end, b', of which rod is secured by an eye-bolt to the hind bolster of the wagon, all as shown in figs. 1 and 2.

At the opposite end of the shaft D is secured another arm, b', similar to the lower end, b, of C, and which stands in the same position on the under side of the shaft, and is also attached to a rod, F, running back to the bolster, the bosses upon the insides of these arms or levers serving as collars to prevent any play of the shaft endwise in the brackets.

It will be seen, when the parts are thus arranged, that by forcing the upper end of the lever C back, the end of rod F will serve as a fulcrum, and the shaft D be carried back, sliding in the brackets, and force the rub-blocks against the wheels.

To operate the lever C, I attach to its upper end a bar or rod, G, which extends nearly to the front end of the wagon, and has a handle or ring, e, on it, near the front end, and joint this rod to a bar, H, which bar is pivoted at its other end to the metal frame or plate I, bolted to the wagon-body, all as clearly shown in figs. 1 and 2, the bars G and H forming a toggle-joint, so that when the rod G is drawn backwards and forced downwards, by placing the hand or foot in the ring e, the lever C will be carried back with great force, the power increasing as the bars get nearer in line. The rod G is forced down until it and bar H stand in line, and a little past, when bar H will strike against the frame I and prevent its further movement, and in this position the bars will stand until released by hand.

When the brake is to be released, the handle e is drawn up, releasing the toggle and allowing the lever C to come forward and unlock the wheels. The forward motion of the handle being continued, it will pass forward and the bars G and H fold down out of the way, only the handle e projecting above the edge of the body, as shown in red lines.

When the rub-block wears so thin as not to hold the wheels tightly, the lower end of bar H is detached and pivoted to a hole further back in bar I, there being a series of holes, e, provided for that purpose, as shown in fig. 1.

To allow of the adjustment of the block when one wears thinner than the other, so that they may bear equally against the wheels; I attach the rear ends of rods F to eye-bolts *m*, which pass through the bolster, and have thumb-nuts *a* for tightening them up, as shown in figs. 1 and 2.

A brake thus constructed is very cheap, strong, and effective, occupies but little room, and is quickly and easily operated, and may be easily attached to any wagon in a few minutes.

By turning off the nuts *a* and removing the pivot holding the lower end of the bar H, the brake may be taken off, by sliding the shaft out of the brackets.

All chains, springs, ropes, ratchets, &c., are dispensed with, and a brake obtained which gives far better results.

Having thus described my invention, what I claim, is—

A brake consisting of the shaft D, having rub-blocks attached, held in by the rods F, and operated by the lever C and H, connected by the rod G, all substantially as described.

DAVID PHILIPS.
